UNITED STATES PATENT OFFICE

NAT THOMPSON, OF CHICAGO, ILLINOIS, ASSIGNOR TO COE LABORATORIES, INC., OF CHICAGO, ILLINOIS, A CORPORATION OF ILLINOIS

DENTAL FURNACE

Application filed August 9, 1929. Serial No. 384,857.

This invention relates to dental furnaces and may be characterized as an improvement in dental furnaces of the type illustrated and described in my copending application, Serial No. 321,016, filed November 21, 1928.

While these furnaces are referred to in the above application as being particularly suitable for fusing porcelain dental work, it is to be understood that the present invention is not limited to use with particular materials, but may be employed as suitable or desired.

The object of the present invention is to eliminate the platinum windings or coils heretofore commonly employed in devices of this sort. I have found that these windings are rather short lived and that it is a difficult matter to provide for their renewal without renewing either the entire muffle or the entire lining employed in connection therewith.

Another object is to provide a generally improved, simplified and inexpensive heater that will not burn out as quickly as the heater coils heretofore employed and a heater that may be renewed in whole or in part conveniently and expeditiously.

Another object is to provide an improved muffle or oven structure, together with an improved lining and an improved mounting therefor.

According to the present invention, the heater is composed of elements which are, preferably, in the form of bars of carborundum or a carborundum compound or other equivalent material having the desired heat resisting properties. Bars of this sort are now known on the market as "glow bars" and these bars are suitable for the purpose of this invention. According to the present invention, I arrange a pair of these bars vertically within the interior of the muffle chamber and a third or bridging bar of this sort is arranged horizontally across and connects the upper ends of the vertical bars forming an inverted generally U-shaped heater.

Another object of the present invention is the provision of a muffle, which will accommodate the heater bars and which will direct the heat radiation therefrom, preferably to

a substantially common center or to a substantially common field in which field the porcelain dental work or other material is adapted to be disposed.

Another object is to provide a uniform 55 temperature within the muffle chamber. This is obtained by an even radiation of the heat through the chamber and by making the chamber of such contour and proportions relative the work carrier receiving opening 60 that this uniformity in radiation is obtained and not interfered with. This uniformity has not been obtained in other dental furnaces.

The furnace of the present invention is 65 preferably provided with a suitable liner and the bottom of the muffle preferably has a suitable baffle plate.

The lower ends of the vertical bars preferably extend down through the baffle plate 70 for connection in the electrical heater circuit and, where the bridging bar is disposed above the top of the liner, the upper ends of the vertical bars preferably extend through the top of the liner for contact with the bridging bar. In order to dissipate and prevent the collection of heat and injury to or 75 burning out of the heater bars, particularly along the openings through the baffle at the bottom and along the openings through the liner at the top or either of them, I provide for maintaining cool areas around the bars at these points and for effectively dissipating the heat along these regions. 80

Some dental materials, with which the 85 present furnace is adapted for use, require the application of a temperature of the order of 2400° F. to 2500° F. in the neighborhood of four minutes for fusion and the furnace of the present invention is adapted to provide and withstand such temperatures. 90

Other objects and advantages of the present invention will appear from the following detailed description, taken in connection with the accompanying drawings, in which:

Figure 1 is a top plan view of a furnace embodying the present invention;

Figure 2 is an end view, taken from the right in Figure 1, with the base of the fur- 100

nace in elevation and the muffle in section on the line 2—2 of Figure 1;

Figure 3 is a front elevational view of the furnace with the base of the furnace in elevation and the muffle in section on the line 3—3 of Figure 1;

Figure 4 is a diagram of the electrical circuit of the furnace;

Figure 5 is a fragmentary detailed section showing the contact and supporting arm for one of the vertical heater bars.

Figure 6 is a fragmentary detail section taken on the line 6—6 of Figure 1.

Referring to the drawings, 10 designates 15 a suitably enclosed base, supported upon a bottom base plate 11 and covered by a top plate 12. The plates 11 and 12 are preferably of suitable insulating material, such as fiber, "asbestos board", or the like. The bottom of the base plate 11 is provided with supporting feet 13, which may be in the form of buffer supports.

Secured at their lower ends at 14 upon the top plate 12 and projecting upwardly from 25 the plate 12 are a pair of hollow posts or standards 15 supporting the muffle or vertical oven 16. The muffle 16 comprises an endless generally elliptical open base 17, a baffle plate 18 preferably formed of fire clay or some 30 other suitable high refractory material, an inner liner 19 also preferably formed of fire clay or some other suitable high refractory material, a surrounding jacket 20 of suitable insulating material, such as asbestos fiber, 35 "Sil-O-Cel", or the like, a metal shell 21 enclosing the jacket 20 and the outer periphery of the baffle plate 18 and a cover 22, which may be of sheet metal and preferably has a marginally depending flange 23 telescoping 40 over the upper end of the shell 21. The shell 21 is secured at its upper end in the depending and endless molding-like part 23 by screws 24 and the lower end of the shell 21 is secured in the base band 17 by screws 25. The 45 base, which as pointed out, is preferably in the form of a generally elliptical open figure, has marginally thickened openings 28 and, as shown in Figure 6, the upper ends of the standards 15 are solid and of reduced diameter, as indicated at 29.

These reduced ends fit through openings 28 and support the base 17 and thereby the muffle 16 upon the standards 15. Set screws 31 may be threaded through the outer wall 55 of the channel section for securing the base upon the upper reduced ends of the standards.

The lining 19 is in the form of an inverted generally cup-shaped member of generally 60 elliptical horizontal section with its inner periphery defining a generally elliptical muffle or oven chamber 35 and its outer periphery fitting relatively closely in a cavity or recess 36 formed in the jacket 20 and of generally elliptical contour conforming with the

elliptical outer periphery of the lining 19. The lower end of the lining 19 is shown as terminating short of the bottom of the jacket 20 and the baffle plate 18 has a raised part 37 fitting up into the lower end of the cavity 36 and preferably against the lower end of the lining 19 with its outer periphery of elliptical contour conforming with the inner periphery of the cavity 36.

The heater is composed of elements in the form of bars of carborundum or a carborundum compound or other suitable or equivalent material having the desired heat resisting properties. Bars of this sort are, as already pointed out, now known on the market as "glow bars" and these bars are suitable for the purpose of this invention, so that a further detailed description of the material or composition of these bars is believed unnecessary here. According to the present invention, I arrange a pair of these bars 40 and 41 vertically within the interior of the chamber 35 and a third or bridging bar 42 of this sort is arranged horizontally across and connects the upper ends of the bars 40 and 41 forming an inverted generally U-shaped heater.

The bridging bar 42 is disposed above the top 43 of the lining 19 and the top 43 has openings 44 through which the upper ends of the bars 40 and 41 have access to and good contact with the bar 42. The lower ends of the bars 40 and 41 extend down through openings 46 in the baffle plate 18 and are supported and connected into the electrical circuit at their lower ends by metallic spring arms 48. In order to dissipate and prevent the collection of heat and injury to or burning out of the heater bars 40 and 41, particularly along the openings 44 and 46, the openings 44 and 46 are preferably tapered, as shown. The tapering of the openings 44 and 46 removes the walls of the lining 19 from the bars 40 and 41 along these openings, so that heat is not confined along these areas of the bars, such as might occur if the openings 44 and 46 conformed more closely with the bars. In this manner, cool areas are maintained along the bars at these points and the heat is effectively dissipated along these regions of the bars.

As already pointed out, some dental materials, with which the present furnace is adapted for use, require the application of temperatures of from 2400° F. to 2500° F. in the neighborhood of four minutes for fusion. For example, the S. S. White dental porcelain requires the application of a temperature of about 2440° F. for four minutes for fusion. In the furnace of the present application, the lining 19 will withstand temperatures up to 3000° F., without fracturing, and will effectively insulate and keep the heat within the chamber 35 under such temperatures and the heater bars 40, 41 and

42 will stand up under temperatures up to 2500° F. without burning out. This materially increases the utility of the present furnace and adapts the same for dental work under conditions which platinum wound muffles would not withstand.

The upper wall 43 of the lining 19 is preferably depressed to space it from the horizontal heater bar 42 and this space is preferably filled with a suitable insulating material at 50. I find that providing this insulation 50 between the heater bar 42 and the top wall 43 of the lining provides a protection for the bar 42, so that this bar will not be heated materially from the heat of the furnace compartment 35, that is, it will not be heated materially beyond its own heating action and its life is thereby prolonged. The bar 42 serves as an electrical connector across the upper ends of the heater bars 40 and 41 and preferably without material heating action in itself.

The contact and supporting arms may be secured to the base 17 each by a bolt 52, as shown in Figure 5. The bolt 52 has a head 53 disposed in a socket 53a in the base 17 with an insulating washer 53b between it and the integral flange 53c on the base 17 at the lower end of the socket and around the opening 53d through which the shank of the bolt 52 passes with a space 53e between it and the flange 53c. The contact arm 48 is provided with an aperture 54 through which the pin 52 extends and an insulating washer 55 is interposed between the mounted end of the arm and the base of the channel with a nut 55' threaded upon the bolt 52 and adapted for clamping the bolt 52 and washers 53b and 55 in place.

40 A wing or thumb nut 58 is threaded upon the stem 52 below the mounted end of the arm 48 and is adapted to be threaded upwardly to clamp the mounted end of the arm firmly in place with the conductor 67 clamped between the arm 48 and the nut 58 and in good electrical contact with the arm. The outer end of each arm 48 is cupped at 60 to receive the lower end of the respective bar 40 or 41, which may be rounded or correspondingly formed for cooperation therewith. The arms 48 are, preferably, spring arms and, in addition to connecting the bars 40 and 41 into the electrical circuit are, preferably, biased upwardly to not only support the bars 40 and 41, but to press these bars upwardly and hold the upper ends in good contact with the bar 42.

The upper ends of the bars 40 and 41 may be rounded and the lower surface of the bar 42 is, preferably, provided with depressions or pockets 62 for receiving these rounded or otherwise suitably formed upper ends of the bars 40 and 41, as shown in Figure 3.

Referring to the diagram of Figure 4, the device is provided with suitable binding posts

or terminals 65, to which the two sides of the supply circuit 66 may be connected in the usual manner. The supply circuit may be at 110 volts or at any other suitable voltage. The terminal 65 may be suitably mounted upon the base 10 and from one of these terminals a conductor 67 extends as through the interior of the base 10, which may be enclosed by suitable vertical side and end walls preferably of mesh or open work construction as shown for cooling the interior of the base. The conductor 67 leads up from the interior of the base 10 through one of the standards 15 and out through an opening 68 in this standard, which may be hollow only from the bottom of the standard up to the opening 68. The end of the conductor which is led out through the opening 68 is clamped as shown in Figure 5, against the mounted end of the adjacent contact arm 48 by the nut 58. A second conductor 69 extends from the interior of the base 10 up through the other standard 15 and out through an opening 70 and is similarly connected with the other contact arm 48. Within and housed by the base 10 is a suitable resistance unit 72. This resistance unit 72 is preferably in the form of a carbon pile resistance longitudinally disposed in the bottom of the base 10 and preferably to one side of the center of the base, so as to not interfere with the action of the vertical rack bar 73, the lower end of which extends down through the upper plate 12 and into the interior of the base enclosure 10.

Carbon pile resistance elements of this sort are well known in the art and a detailed description of the same is believed unnecessary here. Suffice it to say that one end of this resistance element is connected (Figure 4) by a conductor 75 with the other terminal 65, while the opposite end of the resistance element 72 is connected through the conductor 69 with the associated contact arm 48. One end of the resistance element 72 is supported upon a panel element 78, which is adapted to be secured to one of the end walls of the base enclosure 10, as shown in Figure 2. This panel which is also preferably of mesh or open work construction and may be removable with the resistance 72 as a unit and secured in place by screws or the like (not shown). In the illustrated embodiment a small separate removable panel 99 is shown which panel 99 carries the resistance 72 and may simply be fastened to the end wall with the resistance element 72 extending through an opening in the end wall and internally into the base enclosure by screws 100 as shown in Figure 3. Externally of the base enclosure 10, the resistance element 72 is provided with a suitable control knob 79. By manipulating this control rod 79, the carbon buttons or other elements may be pressed more tightly together to reduce the resistance in the circuit and by manipulating the control rod or

turning it in the opposite direction, for example, the pressure may be released and the carbon elements loosened with respect to each other to increase the resistance in the circuit.

5 A voltmeter 82 is, preferably, connected into the electrical circuit, as shown in Figure 4 and is mounted upon the top of the base enclosure 10 for the purpose of indicating the voltage in the circuit. A switch 83 (Figure 10 4) connected into the circuit is adapted for opening and closing the circuit at will.

For the purpose of indicating whether or not there is a current flow to the circuit when the switch is closed or open, a pilot light 84, 15 in the form of an incandescent bulb, is, preferably, connected in parallel with the circuit. This bulb 84 is, preferably, mounted within the base enclosure and is visible from the outside through a suitable phresol 85 in the 20 front wall of the base enclosure, as shown in Figure 3.

For the purpose of indicating, at all times, the temperature within the chamber 35, a 25 thermo-couple 86 is mounted in the wall of the muffle 16, as shown in Figure 2. This thermo-couple passes through an insulating sleeve 87 fixed in the wall of the jacket 20 and its inner end extends into and is exposed to the temperatures within the oven or muffle 30 chamber 35. A meter 88, which may be of the galvanometer type, is disposed on the top of and constituting a unit with the instrument 82, as shown in Figure 3, and this meter is connected through suitable leads 89 with 35 the thermo-couple 86 for the purpose of indicating, by the position of the pointer 90 of the meter which may play over a suitable graduated scale, the temperature within the compartment 35. The thermo-couple 86 and 40 meter 88 constitute a pyrometer. The showing of these parts is more or less diagrammatic, but is believed sufficient to enable those skilled in the art to clearly understand the association of these features with the 45 present invention.

The work carrier comprises a disk 92, which is preferably made of fire clay or other suitable high refractory material. The disk 92 is carried upon the upper end of the rack 50 bar 73, which is arranged to slide through an opening in the top plate 12 and extends, at its lower end, down into the base enclosure 10.

Removably positioned upon the disk 92 is an inverted crucible 93, which serves as a 55 support for the work to be baked or fused.

The crucible 93 is, preferably, formed of fire clay, alundum, or other suitable high refractory material.

The rack bar 73 is moved vertically by 60 means of pinion 94, the teeth of which engage the teeth of the rack bar. The pinion 94 is fixed upon a shaft 95 and disposed within the base enclosure 10. The shaft 95 is journaled in suitable bearings in the base enclosure and one end extends out through the 65

adjacent end wall of the enclosure and is provided with a knob or finger piece 96 for turning the shaft in either direction selectively, at will. Obviously, by turning the finger piece 96, the disk 92 may be raised or lowered, as desired.

70 The disk 92 has the upwardly tapered or conical portion which fits into an opening 97 in the baffle plate 18 and is provided with an annular flange or shoulder at its lower end, which engages up beneath the baffle plate. The work designated at 98 is supported upon the closed top of the crucible and is held substantially centrally disposed within the muffle chamber 35 thereby, as 75 shown in Figure 3. The interior elliptical contour of the lining 19 is such as to accommodate the vertical bars 40 and 41 and, at the same time, directs the heat radiation from these bars to substantially a common center, or to a common field. The crucible 93 supports the work 98 at this common center or in this common field, so that the generally elliptical internal contour of the muffle not only accommodates the heater bars, but by 80 directing the heat radiation from these bars to substantially a common center, provides a uniform temperature within the muffle chamber. This is an important aspect of the 85 present invention.

In the operation of the furnace of the 90 present invention, the finger piece 96 is turned to move the crucible 93 downwardly from the bottom of the muffle, so that the work may be placed on the top of the crucible. The pinion 94 is then turned in the opposite direction, to elevate the rack bar with an accompanying movement of the crucible up into the muffle into the position shown in 95 Figure 3. The work 98 then occupies a position in substantially the center of the chamber 35, whereupon the rheostat or resistance element 72 may be adjusted by the knob 79 to provide the desired resistance therethrough and the current from the line is then connected by closing the switch 83. The 100 bars 40 and 41 thereupon become highly heated and the chamber 35 is heated to a high degree, which is indicated upon the instrument 88. The heat is directed by the inner surface of the lining 19 to the common center, in which the work 98 is arranged and the heating continues until the desired results are obtained. When the operation is completed, the circuit may be opened by the switch 83 and the work 98 is then removed from the muffle by lowering the crucible 93 as previously described.

I do not intend to be limited to the precise details shown or described.

I claim:

1. In an electrical furnace, a muffle defining a heating chamber, closed at one end and open at the opposite end, a connecting bar 105 extending along the closed end of said chamber

ber, a baffle plate for the open end of said chamber, said baffle plate having openings therethrough, a pair of heater bars disposed along the sides of said chamber and extending through the openings in said baffle plate, and means externally of said plate for supporting said last bars and holding same in contact with said first bar.

2. In an electrical furnace, a muffle defining 10 a heating chamber, closed at one end and open at the opposite end, a heater bar extending along the closed end of said chamber, a baffle plate for the open end of said chamber, said baffle plate having openings therethrough, a pair of heater bars disposed along 15 the sides of said chamber and extending through the openings in said baffle plate, and means externally of said plate for supporting said last bars and holding same in contact 20 with said first bar, said baffle plate openings being tapered to dissipate and prevent the collection of heat along the bars adjacent their passage through the baffle plate.

In witness whereof, I hereunto subscribe 25 my name this 1st day of July, 1929.

NAT THOMPSON.
